(57) **CLAIM**

The ornamental design for a lamp as shown and described.

DESCRIPTION

FIG. 1 is a perspective view of a lamp.

FIG. 2 is a front view of the lamp.

FIG. 3 is a rear view of the lamp.

FIG. 4 is a left side view of the lamp.

FIG. 5 is a right side view of the lamp; and,

FIG. 6 is a top view of the lamp.

The broken lines illustrate portions of the lamp that form no part of the claimed design.
